LINDSLEY SCHEPMOES, OF HASBROUCK HEIGHTS, NEW JERSEY, ASSIGNOR TO THE SAFETY CAR HEATING & LIGHTING COMPANY, A CORPORATION OF NEW JERSEY.

LIGHTING-FIXTURE.

1,045,445.

Specification of Letters Patent. Patented Nov. 26, 1912.

Application filed December 14, 1909. Serial No. 533,093.

To all whom it may concern:

Be it known that I, LINDSLEY SCHEPMOES, a citizen of the United States, residing in Hasbrouck Heights, county of Bergen, and 5 State of New Jersey, have invented new and useful Improvements in Lighting-Fixtures, of which the following is a description.

My invention pertains to that class of lighting fixtures used for the support of incandescent lamps and distribution of light 10 given thereby.

My invention has for its particular object to support an electric lamp and hold a shade or reflector in proper operative relation thereto in such manner as to direct the rays in a desired direction.

A further object of my invention is to provide means whereby the shade may be clamped in a given relation with respect to 20 the lamp and held rigidly in this position and also to be readily removed by proper manipulation when desired.

In the drawing Figure I is a vertical section and partial elevation of a fixture embodying one form of my invention. Fig. II is a vertical section and partial elevation of a fixture embodying a modified form of my invention. Fig. III is a perspective of one 25 of the parts of my improved fixture shown in section in Figs. I and II as will herein-after be more plainly explained.

In Fig. I, 1 represents any suitable type of bracket or other support provided with the depending threaded nipple 2 upon which is threaded an ornamental bonnet 3 provided at its lower portion with a flange 4 which is preferably knurled so as to be easily turned by hand. 5 represents a metal spinning or bonnet free to slide over the threads of the 30 member 2 and provided at its lower portion with the conical flange portion 6. 7 is a bonnet-shaped member attached to the member 2 as indicated and having its lower or body portion formed of independent fingers 8 as 35 shown more plainly in perspective in Fig. III. The lower portion of the fingers 8 is so shaped that when pressed inwardly by a downward movement of the conical member 6 of the member 5 they will fit into the 40 flange 9 of the top of the shade 10 intended to be held by the fixture as shown in Fig. I. 45 11 represents the incandescent lamp or bulb supported by the socket 13 which is screwed into the internal bore 12 of the bracket or 50 other support 1 through which bore the

wires are led to proper connections within the socket 13.

Referring to Fig. II in which like numerals are used to indicate like parts it will be noted that the device shown in Fig. II is 60 the same as that shown in Fig. I with the exception that the loose spun bonnet member 5 is omitted and the member 3 is so shaped as to have an internal conical bore adapted to press the fingers 8 into the flange 65 9 of the shade 10 when the bonnet 3 is moved in a downward direction as by being screwed downwardly on the threaded portion 2.

The operation of my improved invention is substantially as follows:—Referring to 70 Fig. I and starting with the shade in place and the various parts shown in the position shown in the drawing, if it be desired to clamp the shade a little more firmly in the fixture, the flange 4 may be turned in such 75 direction that the member 3 will move downwardly upon the threaded portion 2 and press the member 5 downwardly and crowd the flange portion 6 upon the fingers 8 and force the same more tightly into the flange 80 9 of the shade 10. If it be desired to remove the shade the flange 4 may be grasped and the member 3 rotated so as to move upwardly upon the threaded portion 2 until the member 5 may be raised so that there 85 will be sufficient room between the fingers 8 and the inside of the conical portion 6 that the shade may be sprung out of the fingers 8 in a well-known manner. The shade may readily be replaced by springing the same in 90 place under the fingers again and then the bonnet 5 may be dropped upon the fingers and if the member 3 be screwed down firmly the shade will be held rigidly in place.

Referring to Fig. II and starting with the 95 parts in the positions shown in the drawing, if it be desired to more firmly grip the shade the flange 4 may be readily grasped by hand and the member 3 turned in such direction that it will move downwardly upon the 100 threaded portion 2 and thus owing to the conical shape of its inner surface force the fingers 8 more tightly into the flange 9 of the shade. If, however, it be desired to remove the shade the member 3 may be rotated so as to move upwardly upon the 105 threaded portion 2 until sufficient clearance is left between the fingers 8 and the interior of the member 3 that the shade 10 may be sprung out in a well-known manner. The 110

shade may readily be replaced by springing it into the fingers 8 and then if the member 3 be revolved so as to move downwardly upon the threaded portion 2 the same will crowd the fingers 8 upon the flange 9 in such manner as to hold the shade firmly in place. If desired, the fingers 8 may be so shaped that they will normally tend to open and then as the member 5 in Fig. I or the member 3 in Fig. II is raised the fingers will remain in contact with the inner conical surface and simply open sufficiently to release the flange 9 in a well-known manner.

From the foregoing it will be obvious that I have produced a lighting fixture adapted to hold an electric lamp in place and firmly hold a shade in operative relation thereto in such manner that the same will not rattle when the fixture is subjected to severe vibration as when used in railway cars. Further, the various parts of my improved fixture remain at all times in operative relation and no parts have to be removed during the process of taking out or putting in shades and thus the danger of loss during this process is avoided.

It will also be noted that my improved fixture is of such type as will permit of ornamental design inasmuch as the shade engaging parts are practically concealed by an ornamental bonnet.

I do not wish in any way to limit myself to the exact constructions or modes of operation set forth in the above description for it is obvious that considerable change in the form of fixture may be made without departing from the spirit of my invention which is as set forth in the following claims:

1. A lighting fixture comprehending means for supporting a source of illumination, combined with means for supporting a shade in operative relation thereto comprehending yielding shade gripping and supporting means and movable means which operates the said yielding means, both independently supported by the first mentioned means.

2. A lighting fixture comprising means for supporting a source of illumination; and means for supporting a shade in co-operative relation to said supporting means, comprising shade gripping means carried by the first mentioned means, and movable means carried by the first mentioned means covering said shade gripping means and adapted to close the same upon said shade.

3. In a lighting fixture comprising means for supporting a source of illumination, the combination with a source of illumination and a shade in operative relation thereto, of means for supporting said shade comprehending a yielding gripping member directly attached to said first mentioned means, and movable means attached directly to said first mentioned means and adapted to press

said yielding gripping means against said shade.

4. A lighting fixture comprehending means for supporting a source of illumination, and a shade in operative relation thereto, flexible shade gripping means attached directly to the supporting means, a movable member mounted directly upon said supporting means and adapted by its motion to operate the yielding shade gripping means.

5. A lighting fixture comprehending a member adapted to support a source of illumination, yielding shade gripping and supporting means attached to said supporting member and a member movable upon said supporting member and adapted to operate the gripping member.

6. A lighting fixture comprehending a member adapted to support a source of illumination, a yielding member attached to the first named member and adapted to grip a shade, means threaded upon said first named member and adapted to operate the shade gripping means by change of position upon said thread.

7. Means for holding a shade comprising a supporting member, flexible shade gripping means attached to said member; a sliding bonnet arranged upon said member and surrounding said means, and provided with an internal conical surface for engagement with the gripping means and adapted to press the gripping means upon a shade; and a bonnet rotatably carried by said member above said sliding bonnet, whereby by rotating said bonnet the sliding bonnet may be caused to grip or release a shade.

8. A lighting fixture comprehending a nipple having means for supporting a source of illumination; means for supporting a flanged shade in operative relation to said source of illumination, comprising a plurality of flexible gripping fingers directly attached to said nipple; a conical bonnet covering said fingers and slidably upon said nipple so as to engage and force said yielding members against the flange of the shade.

9. A fixture having means for supporting a source of illumination; in combination with means for carrying a shade in co-operative relation to the latter, comprising yielding shade gripping means fixed to said supporting means and surrounding the latter; a member rotatably carried upon said supporting means and surrounding said shade gripping means, and having means for compressing the gripping means upon a shade, whereby the movement of said rotatable member will cause the gripping means to engage or release a shade.

10. A lighting fixture having a supporting portion, a lamp socket carried thereby, yielding shade gripping means surrounding said socket and supported above the same, movable means slidably on said supporting

portion and surrounding said gripping means, and means whereby the movable means may be caused to press said gripping means into supporting engagement with a shade.

11. A lighting fixture having a supporting portion, a lamp socket carried thereby, yielding shade gripping means surrounding said socket and supported free from engagement

10 with the latter, movable means carried by said fixture and surrounding said gripping means and provided with an internal surface adapted to crowd the gripping means into operative engagement with a shade.

15 12. Means for supporting a source of illumination, having in combination, a supporting member; a receptacle carried thereby; means for carrying a shade in coöperative relation to said receptacle, comprising a plurality of yielding shade gripping devices supported free from engagement with said receptacle, and movable means adapted to engage the gripping means to crowd the same into operative supporting engagement

25 with a shade.

13. Means for supporting a source of illumination, having in combination, a supporting member; a receptacle carried thereby; means for carrying a shade in coöperative relation to said receptacle and comprising a plurality of yielding shade gripping devices carried by the said supporting member and extending over the said receptacle; and movable means operatively engaged

with the shade carrying means and adapted to crowd the gripping members into supporting engagement with a shade.

14. A fixture comprehending a supporting member, a receptacle for a source of illumination carried thereby; a bonnet 40 shaped member supported between the supporting member and the receptacle, and provided at one extremity with a plurality of yielding shade gripping and supporting means; and a movable bonnet extending over 45 said bonnet shaped member and adapted to press the shade gripping and supporting means into operative engagement with a shade.

15. The combination with a source of illumination, a receptacle for carrying the same, and a supporting member for said receptacle; of shade supporting means, supported free from engagement with said receptacle and extending over a portion of 55 said source of illumination, and comprising a plurality of yielding corrugated gripping members, a shade provided with a flange registering with the shade gripping corrugations, and a movable bonnet carried outside of and extending over the shade supporting means and adapted to press the said corrugations upon the flange.
